UNITED STATES PATENT OFFICE.

KARL ROTTGARDT, OF DAHLEM, NEAR BERLIN, GERMANY, ASSIGNOR TO WESTINGHOUSE ELECTRIC & MANUFACTURING COMPANY, A CORPORATION OF PENNSYLVANIA.

VACUUM TUBE FOR AMPLIFICATION AND OSCILLATION GENERATION.

Application filed September 2, 1921, Serial No. 497,946, and in Germany March 8, 1917.

(GRANTED UNDER THE PROVISIONS OF THE ACT OF MARCH 3, 1921, 41 STAT. L., 1313.)

This invention relates to three-electrode vacuum tubes and more particularly to the arrangement of the electrodes within the tube.

- 5 It is an object of this invention to provide a supporting means for the several electrodes which will space them more closely than has heretofore been possible. This object of the invention relates more particularly to the spacing between the cathode and the grid although it is entirely possible, by following the teachings of this invention, to also locate the anode close to the other electrodes.
- 10 It is a further object of this invention to arrange the grid or control electrode so that the maximum effect of the field of this electrode upon the electron stream will be secured. It is well known that the field of 20 a charged body is more intense near the corners than at other points. The invention makes use of this principle to accomplish this object.

25 Other objects of the invention will be apparent from the following detailed description and the illustrations on the accompanying drawings, wherein

30 Fig. 1 is a view, in perspective, of one form of mounting for the electrodes in a vacuum tube embodying my invention.

35 Fig. 2 is a similar view showing another form, the lower portions of the supports having been omitted.

Fig. 3 is a similar view showing another 40 form.

Figs. 4 and 5 illustrate another form of mounting for the electrodes, Fig. 4 being a section upon the line 4—4 of Fig. 5 and Fig. 5 being a section upon the line 5—5 of Fig. 4.

45 Figs. 6 and 7 are similar illustrations of still another form of mounting for the electrodes, Fig. 6 being a section upon the line 6—6 of Fig. 6^a and Fig. 6^a being a section upon the line 7—7 of Fig. 6.

50 Thermionic devices of the type to which this invention relates are ordinarily supplied with a cathode, a grid and an anode. The cathode is heated by current from any suitable source, such as battery. A difference of potential between the cathode and the anode is maintained by means of a battery.

The difference of potential between the anode and the cathode causes a space current to flow. This current is controlled by 55 changing the potential of the grid. If this grid is close to the cathode, smaller changes in the potential of the grid will be necessary to produce the desired changes in the space current. For this reason, it is desirable to mount the electrodes so that the grid is as close as possible to the cathode. In Fig. 1, the cathode 11, the grid 12 and the anode 13 are each mounted upon a pair of elastic supports. The supports 15 at the 60 left in this figure and the supports 16 at the right are caused, by their elasticity, to move away from one another; they thus put a tension upon the electrodes 11, 12 and 13. When these electrodes are heated and expand, this resilient action of the supports keeps the electrodes from sagging, so that there is no substantial change in their distance apart and no danger of their coming into contact with one another. In order to 65 accomplish this, the supports must be rigidly held at their lower ends. This is done by passing them through a glass press 17 which is part of the material of the evacuated tube.

In Fig. 2 a similar construction is illustrated except that the cathode 21, the grid 22 and the anode 23 are shown as ribbons instead of wires. In order to properly support these ribbons the resilient supports 25 and 26 are also of considerable width. 70 Their lower ends are secured in place in the same way as the lower ends of the supports 15 and 16, illustrated in Fig. 1.

75 Fig. 3 shows a modification in which the cathode 31 and anode 33 and their supports 35 are like the corresponding parts in Fig. 2. The grid 32 in this figure stands at an angle with the plane of the anode and the cathode. For convenience in illustration, this is shown as if it were a right angle but it is obvious 80 that any angle is possible. If the angle between the grid 32 and the plane of the other electrodes is near 90 degrees, the grid may be supported by wire-like supports 35 and 36, although the other electrodes are supported by ribbon-like supports, as described 85 in connection with Fig. 2.

90 The mounting illustrated in Figs. 4 and 5 has a ring-shaped cathode 41. Preferably,

this is not a complete ring but instead is made in the form of a loop which nearly completes a circumference and the ends of which form the leads by which the heating current for the cathode is conducted. The anode, in this form, consists of a conducting tube 45 which goes through the plane of the ring 41. The grid 43 is in the form of a ring surrounding the anode 45 and contained within the ring 41. The material of this ring-shaped grid is preferably rectangular in cross section so that the grid affords sharp edges, or corners, where its end surfaces join its cylindrical surface. The grid is separated from the tubular anode by a layer of insulation 44 and from the ring-shaped cathode by a layer of insulation 42. The leads 46, which form the ends of the cathode, may also serve as the support for the whole system of electrodes, or, if desired, any other supporting means may be employed.

The mounting illustrated in Figs. 6 and 7 also has a ring-shaped cathode 51. The ends of this cathode may serve as supports, as described in connection with Fig. 5 or any other desired form of support for leading the heating current to this cathode, may be employed. The grid in this form of the device is a ring 52, the radial section of which is preferably U-shaped, so that the two flanges of the ring extend beyond the circumference of the cathode 51, while the cylindrical part of the grid is within the cathode. The cathode 51 and the grid 52 are separated by insulation 53, preferably this insulation does not extend out as far as the edges of the flanges on the grid 52. The anode 56 is similar in shape to the grid. The tubular part of the anode is within the tubular part of the grid and the flanges of the anode do not extend outward as far as the flanges of the grid. Insulation 54 separates the anode 55 from the grid 52. Preferably, this insulation does not extend to the edges of the flanges on the anode and, even if it should do that, it ought not to extend to the edge of the flanges on the grid.

In the operation of the tube, the electron stream from the cathode to the anode, must go by the grid. In the form shown in Fig. 1, the grid 12 being very close to the cathode 11, enables it to have a strong influence upon the electron stream. In the form shown in Fig. 2, the grid 22 extends for considerable distance parallel to the electron stream and so readily exerts a considerable influence thereon. In the form shown in Fig. 3, the grid 32, being oblique to the plane of the other electrodes, the electron stream must pass around the edges of the grid. The charge upon the grid produces a stronger field at the edges than elsewhere. The electron stream, therefore, is obliged to pass through the strongest part of the field of

the grid and so is readily influenced. In the form shown in Figs. 4 and 5, the electron stream between the filament 41 and the anode 45 is obliged to pass by the corners of the grid 43 and so is subjected to the action of the strongest part of the field of the grid. In the form shown in Figs. 6 and 7, the electron stream from the cathode 51 and the anode 55 is obliged to go around the edges of the flange 52 and there is acted upon by the strongest part of the field of the grid.

It has been found by experiment that tubes may be made in the way described herein, so that the distance between the cathode and the grid is not more than a few tenths of a millimeter, and, with such tubes, a change in the potential of the grid amounting only to a fraction of a volt is sufficient to control the electron stream even when the plate potential is large.

The electrodes used may be wire or strips of platinum or tantalum. When strips of foil are used it is necessary that considerable care be employed in cutting out the strips, in order that they may be mounted at the small distance apart, illustrated in Fig. 2. Ordinary foil may be used for all three electrodes or, if desired, the grid may be perforated, as illustrated in Fig. 3.

For the forms illustrated in Figs. 4 and 6, the tubular anode may be made of any suitable metal, such as tantalum, platinum, nickel, copper, etc. The insulation used may be either mica or any of the usual oxides.

Although I have illustrated a limited number of forms of supports embodying my invention, it is obvious that many other forms will come within the spirit of the invention, and I, therefore, do not desire the patent granted to be limited except as necessitated by the prior art or indicated by the claims.

I claim as my invention:

1. In a thermionic device, an anode, a control electrode, a cathode and solid insulating means separating said electrodes and in intimate contact with each, whereby relative movement of the electrodes is positively prevented and the device is rendered non-microphonic.

2. A thermionic device including a tubular anode, a ring-shaped cathode and spool-shaped grid between them, the flanges of the grid projecting beyond the circumference of the other electrodes.

3. In a thermionic device, three concentric ring-shaped electrodes and solid insulation separating said electrodes, the thickness of said insulation being approximately the same as the thickness of the material of the electrodes.

In testimony whereof I affix my signature.

DR. KARL ROTTGARDT.
